COMBINATION CIGARETTE DISPENSER AND SAVINGS BANK

Maurice J. Auerbach, East Cleveland, Ohio

Application February 17, 1949, Serial No. 916

Term of patent 14 years

(Cl. D52—3)

To all whom it may concern:

Be it known that I, Maurice J. Auerbach, a citizen of the United States, residing at East Cleveland, county of Cuyahoga, and State of Ohio, have invented a new, original, and ornamental Design for a Combination Cigarette Dispenser and Savings Bank, of which the following is a specification, reference being had to the accompanying drawing, forming a part hereof.

Fig. 1 is a perspective view of a combination cigarette dispenser and savings bank, showing my new design;

Fig. 2 is a side elevational view, and

Fig. 3 is a top plan view thereof.

I claim:

The ornamental design for a combination cigarette dispenser and savings bank, substantially as shown.

MAURICE J. AUERBACH.
